Primary Examiner — Elizabeth A. Albert(74) *Attorney, Agent, or Firm* — The Belles Group, P.C.(57) **CLAIM**

The ornamental design for a pochade box, as shown and described.

DESCRIPTION

FIG. 1 is a front top perspective view of a pochade box in accordance with the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The longer broken lines in FIGS. 1-7 illustrating portions of the pochade box are included to show features that form no part of the claimed design. The dotted broken lines at the corners of the bottom in FIGS. 1, 2, and 3 define the bounds of the claimed design and form no part thereof.
